(57) **CLAIM**

The ornamental design for a knee compression sleeve, as shown and described.

DESCRIPTION

FIG. 1 is a front right side perspective view of a knee compression sleeve of the instant invention, shown in a position of use.

FIG. 2 is a top view thereof shown in a position of rest.

FIG. 3 is a rear view thereof shown in a position of rest.

FIG. 4 is a side view thereof shown in a position of rest the opposite side being a mirror image thereof.

FIG. 5 is a bottom view thereof shown in an open position; and,

FIG. 6 is a top view thereof shown in an open position. The broken lines showing a human leg are for the purpose of illustrating environment and form no part of the claim.

1 Claim, 3 Drawing Sheets# US D800,324 S
